UNITED STATES PATENT OFFICE.

GEORGE TENNIE, OF CHICAGO, ILLINOIS.

SIGN-FASTENING.

1,079,617.

Specification of Letters Patent. Patented Nov. 25, 1913.

Application filed April 15, 1913. Serial No. 761,382.

To all whom it may concern:

Be it known that I, GEORGE TENNIE, a citizen of the United States, residing at Chicago, in the county of Cook and State 5 of Illinois, have invented certain new and useful Improvements in Sign-Fastenings; and I do hereby declare the following to be a full, clear, and exact description of the invention, such as will enable others skilled 10 in the art to which it appertains to make and use the same.

This invention relates to new and useful improvements in sign fastenings, and has for its object to provide a device which is 15 formed integrally with a sign and by means of which the sign may be held firmly in position on a wall or similar structure.

Another object of my invention is to provide a means by which a sign may be attached and clamped in such a way that accidental removal of said sign will be substantially eliminated.

A still further object of my invention is to provide a sign of the above character, 25 which will have fasteners formed integrally therewith.

With the above and other objects in view, I will now proceed to describe my invention in the following specification and accompanying drawings, in which,

Figure 1 is a top plan view of a sign, as it would appear in the blank, showing the prongs in their flat position; Fig. 2 is an edge view of my improved sign showing 35 the same as it would appear when being applied to a wall in the first operation; Fig. 3 shows the sign in a second position; and Fig. 4 shows the sign after it has been attached.

Referring to the drawings by characters of reference, 5 indicates the body portion of my improved sign, having in each corner thereof a tapered slot 6. These tapered slots 6 are spaced inwardly from the edges 40 of the sign and are adapted to form prongs 7 which are provided with the spear points 8. Intermediate the prongs 7 and integral with the body portion of the sign, I prefer-

ably provide a tongue 9 which is adapted to overlie a portion of a wall when the 50 device is applied.

Intermediate the ends of the sign and formed integrally therewith, I preferably provide outstanding prongs 10, which are provided at their outer extremities with 55 spear points 11.

The method of applying the improved sign is as follows: The sign is first struck out of a suitable piece of material and the prongs bent, as shown in Fig. 2. The 60 prongs of one end of the sign are then pressed firmly into the wall at the point where it is desired to place the same, as clearly illustrated in Fig. 2; the sign is then bent upwardly in its middle, as clearly 65 illustrated in Fig. 3, and the prongs on the opposite end are pressed firmly into the wall. Thus it will be seen that the sign will assume a bowed position, as clearly illustrated in Fig. 3. The next operation is 70 to press the prongs 10 into the wall and, when the sign is in its hung position, the body portion 5 will be flattened against the wall, as is clearly illustrated in Fig. 4.

It will be seen from the foregoing that my 75 improved sign is particularly simple in operation and that, as the prongs 10 are pressed into the wall, a clamping action is obtained between the ends of the prongs 7 and the outer edge of the wall, whereby the sign 80 will be held more firmly in place.

While in the foregoing I have shown and described the preferred embodiment of my invention, I wish it to be understood that I 85 may change the specific arrangements of parts without in any way departing from the spirit and scope of my invention as set forth in the appended claim.

Having thus fully described my invention, what I claim is:

In a device of the character described, a 90 body portion, prongs in each corner thereof, tongues at the ends of the body portion intermediate said prongs, said tongues and prongs being integral with said body 95 portion and separated from each other by

slots, laterally extending prongs intermediate the ends of the body portion and formed integral therewith, said laterally extending prongs being bent at right angles to the surface of the body portion and having spear points at their outer extremities, the first mentioned prongs being bent at an angle to the body portion and adapted to hook

in a wall when the device is being put in place.

In testimony whereof I affix my signature in presence of two witnesses.

GEORGE TENNIE.

Witnesses:

JERIAHMIRE D. JONES,
BERT F. KISER.
